UNITED STATES PATENT OFFICE.

ULYSSES D. EDDY, OF NEW YORK, N. Y.

DESIGN FOR SAD-IRON STANDS.

Specification forming part of Design No. **11,459**, dated October 14, 1879; application filed July 19, 1879.
[Term of patent 14 years.]

To all whom it may concern:

Be it known that I, ULYSSES D. EDDY, of New York city, in the county of New York, and State of New York, have invented a new Design for Sad-Iron Stands; and I do hereby declare the following, when taken in connection with the accompanying drawings and the letters of reference marked thereon, to be a full, clear, and exact description of the same, which said drawing constitutes part of this specification, and represents a top view.

This invention relates to a design for the article known to the trade as "sad-iron stands"—that is, the article used upon ironing-tables to rest the iron upon during intervals in its use, so as to prevent its burning the ironing-cloth; and the invention consists in the shape of the stand, as hereinafter described, and shown in the accompanying illustration.

The body A is in the shape of a horseshoe. From the heel ends an extension, B, is made, in handle shape. In the center is an inclosed star, surrounded by the words "Good Luck," all as shown in the accompanying illustration.

I claim—

The design for sad-iron stand, consisting of the horseshoe-shaped body, with handle-shaped extension from the heel ends, with an inclosed star in the center, and the words "Good Luck," all as shown in the accompanying illustration.

ULYSSES D. EDDY.
